UNITED STATES PATENT OFFICE.

JESSE M. YOUNT, OF NEW YORK, N. Y.

WHEEL-GUARD.

958,791.

Specification of Letters Patent. Patented May 24, 1910.

Application filed July 26, 1909. Serial No. 509,534.

To all whom it may concern:

Be it known that I, JESSE M. YOUNT, a citizen of the United States, and a resident of the borough of Manhattan, in the county 5 of New York, city and State of New York, have invented certain new and useful Improvements in Wheel-Guards, of which the following is a specification.

My invention relates to devices designed 10 to be attached to street railway and other cars and to serve the purpose of preventing injury to human beings and animals by guarding the wheels of the car.

The objects of the improvements are, 15 among others, to provide a simple, strong and durable structure of this character which may be easily attached to the car and adjusted to its proper position and which will act with certainty and efficiency at all 20 times and regardless of the position of the car and its wheels.

The invention consists in the construction, 25 combination and arrangement of parts hereinafter described and claimed and illustrated in the accompanying drawings.

In the said drawings, Figure 1 is a plan 30 of a wheel guard and its accessories embodying the improvements, one side of the apparatus being cut away longitudinally. Fig. 2 is a vertical section on the line 2—2 of Fig. 1 looking in the direction indicated by the arrows. Fig. 3 is a vertical cross section on the line 3—3 of Fig. 1.

The device may be said to consist of three 35 principal parts: a tripping device provided with means for resetting; a connecting or transmitting mechanism and a wheel guard proper.

The tripping mechanism consists of a gate 40 A pivotally hung from the bar B mounted between hangers C, secured to the underside of the car platform X, and its connections. A loose collar A', through which the bar B passes, is located at both sides 45 and is connected with the gate through the arm A². A fixed collar D with an arm D' is provided for the resetting pedal, and a like collar E with arm E' provided for the transmitting mechanism. The gate A 50 clears the track Y preferably by several inches and extends across from one track to the other at right angles thereto a short distance beyond said tracks at either side so that any object of considerable size on 55 the tracks will come in contact with the said gate.

The resetting pedal F has an L-shaped arm F' extending down through the car platform and pivotally connected at its lower horizontally turned end with the arm 60 D', so that when the gate swings backward, thereby oscillating the arm D', the pedal will be raised above the floor of the car platform, while, on the other hand, when the pedal is depressed, the arm D' and gate will 65 be oscillated and moved forward to their normal positions. The upper position of the pedal F and connected parts is shown by dotted lines in Fig. 2.

When the gate A encounters an obstacle 70 and is swung backward and upward it also oscillates the arm E' on the collar E and causes the rod G, pivotally connected thereto, to be drawn forward. The opposite end of this rod is pivotally connected with the flat 75 bar H by means of a connecting head G' on the end of the rod G and a vertically turned portion H' at the end of the bar H, so that the reciprocating motion of the rod G is communicated to the bar H and causes the 80 said bar to slide in the hanger guides I secured to the underside of the car platform and causes the downwardly turned rear end H² to press against or recede from the curved plate J. By this means the guard 85 proper, with which the curved plate J is rigidly connected through the upright arm K, is caused to move simultaneously with the gate A at the front of the platform.

The wheel guard proper L is located di- 90 rectly in front of the wheels (dotted lines Figs. 1 and 2) nearest the end of the car and consists of vertical and horizontal parts secured together by arms L', L², re- 95 spectively, connected with a common collar M mounted on the bar N carried by the truck O, a hanger N' connecting the said bar with the trucks. The collar M is loose on the bar N, so that the guard L will freely oscillate thereon. The construction of the 100 guard L is completed by uprights L³ and cross pieces L⁴ of the upright portion and cross pieces L⁵ bolted or otherwise secured to the arms L² and L⁶ of the horizontal portion. At each side of the center of the 105 guard are horizontal pieces L⁶ integral with the upright K carrying the curved plate J and in this manner the guard is connected with the other parts of the mechanism.

Secured to the strip L⁷ on the bottom of 110 the guard by means of a hook R is a tension spring S, the opposite end of which is con-

nected with the hook T on the truck O, and by this means a constant tension tending to draw the guard downward is maintained, so that when the rod G is drawn forward by 5 the backward movement of the gate A and the downwardly turned end H² withdrawn from the curved plate J, the spring S will instantly pull the guard down until its outer end strikes the rails Y. It will be 10 understood that the parts will remain in this position until restored by the depression of the pedal F, as heretofore described, which thrusts the rod G backward against the plate J and restores the guard L to its normal 15 position, the parts being held in this position by the rod G and arm E', which are substantially on dead center.

Near the outer end of the bars L² are depressions L⁸, the object of which is to act as 20 a guide for the wheel guard L by entering the slot of the rail, or where slotted rails are not used, by falling inside the rails, and thus preventing lateral movement.

The curved plate J is of peculiar construction and arrangement and performs very important functions. The rail guard proper and connected parts, including the curved plate J, are all mounted on the wheel truck, and consequently move with the 25 wheels and not with the body of the car. The other parts of the mechanism, however, are mounted on the floor of the car body and must, therefore, move with the car. Consequently at switches and curves a considerable amount of movement of the parts 30 mounted on the body of the car and the parts mounted on the wheel trucks relative to each other is absolutely necessary. At the same time it is imperative that the adjustment of the parts shall not be disturbed and that they shall remain in constant operative position at such times. I have, therefore, devised the curved plate J which is bent to form an arc of a radius drawn from 35 the pivotal point of the wheel trucks, so that the distance from the point of the said plate opposite the turned end H² to the arm E' by which the motion of the guard A is communicated to the wheel guard L is the same, no matter what the angle of the wheel 40 trucks with respect to the body of the car may be. I have also so constructed and arranged this plate and the adjacent parts so that there is no positive connection between 45 them, and this secures two very important advantages: The car may be dismantled or assembled without making or unmaking any connection, and the parts can not become bent or broken through the neglect of workmen to attend to these matters, while, as soon as the car is placed upon the truck, the device is in operative position, it being necessary only to place a block under the guard L or to tie the upright K to the wheel truck. 50 Another important advantage of this con-

struction is that the connection between the forward and rear parts of the mechanism cannot be damaged when the car "splits" a switch, as not infrequently occurs. In the event of such an accident the turned end H² 70 will simply slip off the end of the curved plate J, whereas, in all devices where these parts are connected, instead of being merely in frictional contact, this accident will break or bend the parts and put the entire mechanism out of operation. This also frequently occurs when the car leaves the track or whenever, from any cause, the wheel trucks are turned at a great angle to the car body. 80

What I claim as new is:—

1. The combination of a curved plate mounted on the wheel truck and movable therewith, said plate being adapted to have independent movement, a member adapted 85 to be pressed against the said plate mounted on the car body and a guard connected with the said curved plate adapted to be moved in one direction through the said curved plate. 90

2. The combination of a curved plate mounted on the wheel truck and movable therewith, said plate being adapted to have independent movement, a member adapted 95 to be pressed against the said plate mounted on the car body and a guard connected with the said curved plate adapted to be moved in one direction through the said curved plate, and a spring secured to the said guard for moving it in another direction. 100

3. The combination of a curved plate mounted on the wheel truck and movable therewith, said plate being adapted to have independent movement, a member adapted 105 to be pressed against the said plate mounted on the car body and a guard connected with the said curved plate adapted to be moved in one direction through the said curved plate, and a spring secured to the said guard for moving it in another direction 110 and means secured to the body of the car forward of the said guard for operating the member and adapted to press against the plate. 115

4. The combination of wheels mounted in a truck adapted to have rotary movement, a plate mounted on the said wheel truck curved on an arc struck from the truck pivot, a wheel guard mounted on the truck and connected with said plate, a member 120 inovably mounted on the car and means at the end of the car and outside of the wheel guard for moving the said member toward and from said plate and a spring connected with the truck and with the wheel guard for drawing the said guard downward. 125

5. The combination with a car and a suitable truck, of a curved plate mounted horizontally on a wheel truck and movable therewith, the convex side of said plate fac- 130

ing the nearest end of the car, a member disconnected from said plate and adapted to be pressed against the same mounted on the car body, and a guard connected with the 5 said plate adapted to be moved in one direction through the said plate, and a spring secured to the said guard for moving it in another direction, and means secured to the body of the car forward of the said guard 10 for operating the member adapted to press against the plate.

6. The combination of wheels mounted in a truck adapted to have rotary movement, a plate mounted on the said wheel truck 15 curved on an arc struck from the truck pivot, a wheel guard mounted on the truck and connected with said plate, a member movably mounted on the car and means at the end of the car and forward of the wheel 20 guard for moving the said member toward and from said plate and a spring connected with the truck and with the wheel guard for drawing the wheel guard downward.

7. The combination of wheels mounted in 25 a truck adapted to have rotary movement, a plate mounted on the said wheel truck curved on an arc struck from the truck pivot, a wheel guard mounted on the truck and connected with said plate, a member mov- 30 ably mounted on the car disconnected from the said curved plate and having its rear-most extremity in advance thereof, and means at the end of the car and forward of the wheel guard for moving the said mem- 35 ber toward and from the said plate.

8. In combination with wheels and a wheel truck on which a car is pivotally mounted, a plate mounted on the forward portion of the truck, the said plate being 40 curved on an arc corresponding substantially with the arc described by the portion of the truck to which it is attached, a tripping device forward of said plate comprising a gate or tripping frame hung from the 45 car so as to swing backward upon encountering an obstacle in its path, an arm rigidly connected with the said gate so as to oscillate therewith, a rod loosely connected with said arm and adapted to be recipro- 50 cated by the oscillation thereof and thereby to cause backward pressure on the said curved plate or permit the same to move forward, a fender connected to said plate and means constantly tending to move the 55 lower part of said fender downward and the plate forward, the said arm and rod being substantially in line and on dead center when the parts are in normal position.

9. In combination with wheels and a wheel truck on which a car is pivotally 60 mounted, a plate mounted on the forward portion of the truck, the said plate being curved on an arc corresponding substantially with the arc described by the portion of the truck to which it is attached, a tripping device forward of said curved plate comprising a gate or tripping frame hung from the car so as to swing backward upon encountering an obstacle in its path, a rod 65 connected with the said gate so as to move therewith and thereby to cause backward pressure on the said curved plate or permit the same to move forward, said rod terminating in front of and being disconnected from said plate, a fender connected to 70 said plate and means constantly tending to move the lower part of said fender downward and the plate forward, the said arm and rod being substantially in line and on dead center when the parts are in normal 75 position.

10. In combination with wheels and a wheel truck on which a car is pivotally mounted, a plate mounted on the forward portion of the truck the said plate being 85 curved on an arc corresponding substantially with the arc described by the portion of the truck to which it is attached, a tripping device forward of said curved plate comprising a gate or tripping frame hung 95 from the car so as to swing backward upon encountering an obstacle in its path, an arm rigidly connected with the said gate so as to oscillate therewith, a rod loosely connected with the said arm and adapted to be recipro- 95 cated by the oscillation thereof and thereby to cause backward pressure on the said curved plate or permit the same to move 100 forward, a fender connected to said plate and means constantly tending to move the lower part of said fender downward and the plate forward, the said arm and rod being substantially in line and on dead center when the parts are in normal position, a second arm connected to said gate 105 and out of line with the first named arm and means connected therewith and extending through the floor of the car body for moving the gate to its normal position.

Witness my hand this 21 day of July 110 1909, at the city of New York, in the county and State of New York.
